UNITED STATES PATENT OFFICE.

CHARLES E. GODLEY, OF DETROIT, MICHIGAN, ASSIGNOR TO EDMUND'S AND JONES CORPORATION, OF DETROIT, MICHIGAN, A CORPORATION OF NEW YORK.

LAMP-MOUNTING.

1,223,962.

Specification of Letters Patent. Patented Apr. 24, 1917.

Application filed November 6, 1916. Serial No. 129,718.

To all whom it may concern:

Be it known that I, CHARLES E. GODLEY, a citizen of the United States, and residing at Detroit, in the county of Wayne and State of Michigan, have invented a new and Improved Lamp-Mounting, of which the following is a specification.

This invention relates to means for securing lamps to upright or inclined rods or posts, and its object is to provide a mounting whereby, through the use of interchangeable parts which can be produced at very little cost, the lamp may be mounted on any one of a great variety of supports which differ not 15 only in construction but also in position.

It is often desirable to mount oil lamps on motor vehicles already equipped with electric lamps and these auxiliary lamps are most conveniently mounted on the frames of 20 the windshields. As the lamps are of standard construction and the construction of the windshield supports vary greatly, a mounting that may be adapted to all types of supports is most desirable.

This invention therefore consists in a mounting to secure lamps to the supports for windshields, whether these are inclined or vertical, and comprises an arm on the lamp, a clamping member to engage the support, 30 and a movable jaw that may be positioned to accommodate the mounting to various types of windshield supports.

In the accompanying drawing, Figure 1 is a front elevation of a windshield having 35 lamps secured to its supports by means of this improved lamp mounting. Fig. 2 is a plan of one form of this mounting. Fig. 3 is a front elevation thereof. Fig. 4 is a side elevation thereof. Fig. 5 is a front elevation 40 of a modified form of this mounting. Fig. 6 is a side elevation thereof. Fig. 7 is a plan thereof.

Similar reference characters refer to like parts throughout the several views.

The windshield shown conventionally in Fig. 1 has two panels 1 and 2 and supports or posts 3 and 4. To the posts lamps 5 are secured by means of the mounting illustrated in Figs. 2 to 4 inclusive if the supports 3 and 50 4 lean back, or by means of the mounting shown in Figs. 5 to 7 inclusive when the supports 6 are vertical or at least both in the same vertical plane.

In both of these cases, an arm 10 is secured

to the body 11 of the lamp and is formed 55 with an opening for the clamping bolt 12 having a nut 13 on one end. The split washer 14 may be employed if desired. In order that the bolt may not bend under heavy stress, a grooved shoulder 15 may be formed 60 on the arm 10. The outer arm 16 of the bolt may be formed with a notch to receive the support 4 or 6.

The arm 10 is formed with a small hole to receive the screw 17 which engages in a 65 threaded hole in the beveled jaw 18. The arm and the jaw are formed with rings of inter-engaging teeth 19 to prevent rotary movement and the jaw is formed with parallel teeth 20 between which the support 3 is 70 received. In order to strengthen the union between the jaw and arm, the latter may be formed with a counterbore and the jaw with a cylindrical hub 22 to fit this counterbore. By turning the jaw on the arm, the lamp 75 may be secured in an upright position to supports that not only lean backward but to such as also lean inward. It will be noted that the end of the arm and the jaw are partly cut away so as not to project into the path 80 of the windshield.

Where the supports 6 are vertical or at least are both in the same vertical plane, whether they lean in or out, the jaw 25 need not be beveled. Teeth 26 will be formed 85 thereon to engage the teeth 19 on the arm 10 and teeth 27 to engage the supports. All the remainder of the lamp mounting is the same as that above described. Therefore, to adapt this support to any ordinary type of support, 90 a proper jaw 18 or 25 alone is necessary, and these will be of very few styles and so can be easily kept in stock by lamp dealers.

I claim:—

1. A lamp mounting comprising an arm 95 secured to the lamp and having a circular row of teeth, a jaw mounted thereon and having a row of teeth to engage the teeth on the arm and also provided with teeth to engage a post, and an adjustable member to 100 engage the side of the post opposite said jaw.

2. A lamp mounting comprising an arm secured to the lamp and having a circular row of teeth, a jaw mounted thereon and having a row of teeth to engage the teeth 105 on the arm and also provided with teeth to engage a post, a screw concentric with said rows of teeth to secure the jaw to the arm,

and a hook slidably mounted in the arm and adapted to engage the side of the post opposite said jaw.

3. A lamp mounting comprising an arm 5 secured to the lamp and having a circular row of teeth, a jaw mounted thereon and having a row of teeth to engage the teeth on the arm and also provided with teeth to engage a post, a screw concentric with said rows of teeth to 10 secure the jaw to the arm, and a hook slidably mounted in the arm and adapted to engage the side of the post opposite said jaw,

said arm being formed with a shoulder to support said hook.

4. A lamp mounting comprising an arm 15 secured to the lamp and having teeth, a jaw mounted thereon and having teeth to engage the teeth in the arm and also formed to engage a post, the planes of the set of teeth and of the post engaging surface being at an 20 oblique angle to each other, and adjustable means to force the jaw against the post.

CHARLES E. GODLEY.
